(74) Attorney, Agent, or Firm — Ohlandt, Greeley,
Ruggiero & Perle, LLP(57) **CLAIM**

The ornamental design for an antenna, as shown and described.

DESCRIPTION

FIG. 1 is a perspective view of an antenna showing our new design; and,

FIG. 2 is another perspective view thereof.

The portions of railing shown in FIGS. 1-2 to which the antenna is attached form no part of the claimed design.

1 Claim, 2 Drawing Sheets(56)
